(57) **CLAIM**

We claim the ornamental design for a drill bit, as shown and described.

DESCRIPTION

FIG. 1 is a perspective view of a drill bit embodying the invention.

FIG. 2 is a front view of the drill bit shown in FIG. 1, the rear view being substantially the same as the front view.

FIG. 3 is a side view of the drill bit shown in FIG. 1, the opposite side view being substantially the same as the illustrated side view.

FIG. 4 is a top view of the drill bit shown in FIG. 1; and,
FIG. 5 is a bottom view of the drill bit shown in FIG. 1.

The elements shown in broken lines are for illustrative purposes only and form no part of the claimed design.
